(57) **CLAIM**

The ornamental design for a footwear upper as shown and described.

DESCRIPTION

FIG. 1 is a perspective view of a footwear upper embodying the new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The light-weight broken lines showing a shoe sole depict portions of the shoe that form no part of the claimed design. Further, the light-weight broken lines immediately adjacent the solid line portions of the design form the boundary of the design, with those light-weight broken lines forming no part of the claimed design. The evenly spaced heavy-weight broken lines in the figures depict stitching, which forms no part of the claimed design. The bold broken lines in the figures depict stitching, which forms no part of the claimed design.
